UNITED STATES PATENT OFFICE.

BENTON R. LYSTER AND MORTON J. LYSTER, OF WHITEFIELD, NEW HAMPSHIRE.

APPARATUS FOR DISTILLING WOOD-ALCOHOL AND OTHER PRODUCTS.

941,641.

Specification of Letters Patent. Patented Nov. 30, 1909.

Application filed March 25, 1909. Serial No. 485,657.

To all whom it may concern:

Be it known that we, BENTON R. LYSTER and MORTON J. LYSTER, citizens of the United States, and residents of Whitefield, 5 in the county of Coos and State of New Hampshire, have invented certain new and useful Improvements in Apparatus for Distilling Wood-Alcohol and other Products, of which the following is a specification.

10 Our invention relates to the apparatus used for distilling wood alcohol, etc., and has for its object the provision of apparatus that will save the cost of fuel necessary to operate the stills used to distil alcohol, 15 acetic acid, etc., from the crude pyroligneous acid.

In wood reduction plants as at present operated the crude pyroligneous acid is extracted by placing the wood in an oven and 20 drawing off the vapor through a neck to the condenser. The crude pyroligneous acid is then placed in a still and its temperature raised to a vaporizing heat by means of a steam-coil. In our improved apparatus the 25 still is placed in the neck connecting the oven and the condenser, so as to utilize the heat of the vapor passing through the neck to the condenser to volatilize the acid therein and save the cost of the fuel needed to raise the 30 temperature of the contents of the still by a steam-coil.

Our invention also contemplates the improvement of the still by providing tubes under the distilling chamber and communicating therewith to hold the acid and to increase the surface subjected to the action of the vapor passing from the oven to the condenser, the lower ends of said tubes being connected by pipes and provided with an 40 outlet to draw off the tar and heavy oils from time to time and after distillation. The neck is also provided with a depression under the still to catch any tar that may be released from the vapor by the cooling 45 incident to contact with the still, said depression being also provided with a valve to draw off the tar from time to time.

The construction and operation of our improved apparatus will be described in 50 detail hereinafter and illustrated in the accompanying drawings, in which—

Figure 1 is a side view showing the oven and condenser and the neck and still in section; Fig. 2, a top plan view; and Fig. 3,

an end view of the still with the neck shown 55 in section.

In the drawings similar reference characters indicate corresponding parts in the several views.

A indicates the oven, B the condenser and C the neck connecting the oven and the condenser. The vapor caused by burning the wood in oven A passes through neck C and is condensed in condenser B in the form of pyroligneous acid and heavy oils, tar, etc. 60 The acid has heretofore been placed in a still heated by a steam-coil and the acid volatilized to separate the spirits, acetic acid, and other products therefrom. As stated, this operation required the use of fuel to 70 create the steam necessary to run the stills and added to the cost of the products secured.

Our improved apparatus consists in placing the still 1 in the neck C and providing 75 tubes 2 tapped into its bottom and having their lower ends connected by pipes 3 with a draw-off outlet 4, connected therewith, and provided with a valve 5.

6 indicates the condenser for the products 80 of still 1, and is connected therewith by means of the neck 7. It will be understood that the pyroligneous acid in the still 1 will enter tubes 2 and pipes 3 and the vapors passing through the neck C will heat said 85 contents so as to volatilize the acid and the alcohol and other products will pass off into the condenser 6, the heavier parts of the acid settling into the pipes 3, when they can be withdrawn through outlet-pipe 4. It will 90 be apparent that the reduction of the temperature of the vapor in neck C by contacting with the still 1, tubes 2 and pipes 3 will cause a precipitation of the heavy oils and tar and to catch these we provide the neck 95 with a depression 8 under the still, and also provide a nozzle 9 to draw off said heavy oils and tar when desired. By thus removing some of the heavy products from the vapor before reaching the condenser it will 100 be apparent that the condenser is relieved of the heat thereof, and the condenser is therefore kept cooler for the lighter vapors that pass the still and enter it.

10 indicates a steam-coil in the bottom of 105 the condensing chamber of the still 1 that is connected with any suitable boiler (not shown) by means of supply pipes 11, that

is used to raise the temperature of the still when sufficient heat is not created by the vapor in neck C or to the exclusion of the heat of the vapor when the oven is not in 5 operation.

Having thus described our invention, what we claim is—

In combination with the oven, condenser, and neck of a wood-distilling apparatus, a 10 still mounted in the neck of the apparatus and having a plurality of tubes secured in its bottom and extending downwardly therefrom to hold the contents of the still, the ends of said tubes being connected by pipes, 15 a draw-off tube connected with said pipes, the neck provided with a depression under

said still to catch the heavy oils precipitated by the cooling of the vapors in contacting with the still, and a nozzle tapped into said depression to draw off its contents, substantially as shown and described. 20

In witness whereof, we have hereunto set our hands in presence of subscribing witnesses.

BENTON R. LYSTER.
MORTON J. LYSTER.
